UNITED STATES PATENT OFFICE

PAUL SIPTROTT, OF NEW YORK, N. Y.

CLOCK FRAME AND METHOD OF MAKING SAME

Application filed November 30, 1929. Serial No. 410,861.

The present invention relates to supporting frames for clocks.

Common alarm clocks or the like for ordinary household use are generally of very unsightly and cheap appearance and all are uniform in design since they are machine made. Furthermore, for the support of such clocks just threaded pins are used, which are applied to the side walls thereof.

In order to vary the designs and thereby lend the clock distinct and individual appearance according to the present methods, either the casings themselves are constructed according to certain designs or the clocks are mounted in individual expensive frames. This is true with expensive clocks used in the household.

One object of the present invention is to provide a novel relatively cheap method of forming frames for common or ordinary household clocks, that while ornamental in character are yet capable of quantity production.

A further object is to provide a novel article of manufacture which may readily be adapted as frames for clocks of varying sizes or shapes.

My invention is illustrated in the accompanying drawing which forms part of this specification and in which similar reference characters denote corresponding parts. In the drawing:—

Fig. 1 is a perspective view of a clock with a frame made according to my method, mounted thereon;

Fig. 2 is a top plan view of one form of strip used in producing my frame; and

Figs. 3-7 inclusive are illustrative of the various shapes of clocks and methods of attachment thereto of frames made by my method.

In carrying out my invention a strip 10 of bendable material such as tin alloy, soft iron, copper or the like formed with an ornamental design, as for instance the design of Fig. 2, by casting or stamping or the like, is bent on a form or the like to conform with the shape of the particular clock it is designed to serve as a frame. For instance, the circularly shaped clock 11 of Fig. 1 will of

course require a circularly shaped frame, and in accordance therewith the strip 10 is bent into this shape as shown. The ends of said strip may be bent in reverse direction and suitably curved to form legs 10' and 10'' serving as supports for the clock in lieu of the ordinary threaded pins. As will be seen from the various figures, the degree of curvature and particular form of the legs may be made to harmonize with the particular shape of the frame or clock.

Various means of fastening the bent strip to the clock may be employed. For instance, in Fig. 1 the frame may be fastened to the clock by bolts such as bolt 12 which may screw into the holes present for the usual supporting pins. In Fig. 3 instead of bolting the frame to the clock, a suitable cross piece 13 extending between the legs 14 thereof and so admeasured as to be slightly shorter than the distance between the latter is employed and said legs are bolted thereto. By tightly bolting the former to the latter the frame is tightened about the clock and held in position.

In Fig. 4 no fastening screws are used, but the strip is bent as shown so that a major part of the circumferential surface of the clock may be covered by the frame and then the ends are bent outwardly as shown to form the legs 15.

In Fig. 5 a clock of Gothic arch type may be equipped with a frame formed by suitably bending a strip of the indicated material. The legs 16 curve under the base of the clock and the frame may be fastened to the clock by bolts 17.

In Fig. 6 a clock of polygonal shape e. g. rectangular in this case, is provided with a frame from the above indicated material. In this case the strip is bent to conform with the two upper edges of the clock and also to conform with a portion of the two bottom edges thereof for a short distance and then the legs 18 are formed by bending the ends of said strip away from said two last named edges.

In the modification of Fig. 7 the strip is bent to conform with the two upper edges of the triangular clock and the ends thereof are

bent to form the legs 19 under the base edge of the clock.

It is readily seen therefore that my method of forming clock frames is applicable to any shaped clock and provides a convenient easy way of ornamenting clocks.

Of course my invention may be modified in many ways without departing from the spirit thereof, and I do not wish to be limited to the details shown and described.

What I claim is:—

15. 1. A method of producing frames for clocks, comprising the steps of bending a flat strip of bendable material to the contour of the clock shape, then bending the ends of said strip to form supports for said frame and then mounting said bent strip on said clock.
20. 2. A method of producing ornamental frames for clocks, comprising the steps of bending a wide, flat, ornamented strip of bendable material to the contour of the clock shape, then bending the ends of said strip to form supports for said frame, then mounting the said bent strip on said clock and fastening the same thereto.
25. 3. As an article of manufacture a clock frame comprised of a flat strip of bendable material bent to conform to the shape of a clock, the ends of said strip being bent outwardly to form leg supports for said frame.
30. 4. As an article of manufacture, a clock frame, comprising a wide flat strip of bendable material having a design formed thereon, said strip being bent to conform with the shape of a clock, and legs for said frame formed by bending the ends of said strip outwardly.
35. 5. As an article of manufacture, a clock frame, comprising a flat strip of bendable metal having an ornamental design formed thereon, said strip being bent to conform with the shape of a clock, and legs for said frame formed by bending the ends of said strip outwardly in reverse direction to the principal bend.
40. 6. A frame for a clock or the like, made of a blank of flat bendable material, said blank being formed with a predetermined design and being bent into the shape to fit around the clock and to form supports for the latter and means for tightening said frame to the clock.

In testimony whereof I affix my signature.

PAUL SIPTROTT.
